UNITED STATES PATENT OFFICE.

FRANK M. KENNEDY, OF NEW HARTFORD, NEW YORK, ASSIGNOR TO KENNEDY NOVELTY COMPANY, OF NEW HARTFORD, NEW YORK.

CORD-GUIDING ATTACHMENT FOR BUTTONHOLE-SEWING MACHINES.

1,087,298.

Specification of Letters Patent.

Patented Feb. 17, 1914.

Application filed June 8, 1912. Serial No. 702,636.

To all whom it may concern:

Be it known that I, FRANK M. KENNEDY, a citizen of the United States, residing at New Hartford, in the county of Oneida and 5 State of New York, have invented certain new and useful Improvements in Cord-Guiding Attachments for Buttonhole-Sewing Machines, of which the following is a specification, reference being had therein to 10 the accompanying drawing.

My invention relates to a cord feeding attachment for button-hole sewing machines, and I declare the following to be a full, clear, concise and exact description thereof 15 sufficient to enable any one skilled in the art to which it appertains to make and use the same reference being had to the accompanying drawings in which like reference characters refer to like parts throughout. 20 The object of the invention is to provide a guide adapted to deliver a stay cord relative to certain movements of the presser foot and feed of a button-hole sewing machine, whereby said cord may be presented above 25 the cloth and always in advance of the relative path of the needle.

Furthermore, the invention contemplates certain novel improvements over Letters Patent, No. 1,025,574, granted to me, May 80 7, 1912.

The device is adapted to be attached to any well known type of button-hole sewing machine having a presser foot, feed, and cloth plate which operate in unity to reciprocate the cloth longitudinally of the button-hole, as well as to move transversely thereof, whereby to effect the requisite movements necessary for creating the button-hole. 35

Other objects will be observed by reference to the drawings in which:

Figure 1 is a side elevation of a button-hole sewing machine to which is attached the cording device; Fig. 2 is a front elevation of a button-hole sewing machine, showing 45 the cording device attached thereto; Fig. 3 is an enlarged detail view in plan of the cording attachment, showing the different positions assumed thereby; Fig. 4 is a detail perspective view enlarged of a dog employed; Fig. 5 is a fragmentary side elevation of a button hole sewing machine, showing 50 a modified form of cording attachment secured thereto; Fig. 6 is a front elevation of a button hole sewing machine, showing 55 the cording attachment of Fig. 5 secured

thereto; Fig. 7 is a detail view in plan of the modified form of cording attachment; Fig. 8 is a detail view of a lever employed on the modified form of cording attachment; Fig. 9 is a detail enlarged perspective view 60 of the cording attachment, shown in Fig. 1; Fig. 10, is a detail enlarged view, showing a front elevation of the cording attachment shown in Figs. 1 and 9; Fig. 11 is a detail view in plan of a still further modified form 65 of cording attachment; Fig. 12 is a fragmentary front elevation of the detail shown in Fig. 11; Fig. 13 is a fragmentary view, enlarged of parts of the modified form of attachment shown in Fig. 5; Fig. 14 is a 70 fragmentary detail view, enlarged of the upper portion of an arm employed in Fig. 5; Fig. 15 is a detail view of a button-hole, showing the respective positions of the needle and guide working along the first side 75 of the button-hole.

Referring more particularly to the drawings, the feed portion of presser-foot —1— is represented by 2, and the cloth plate by 3 of a button-hole sewing machine. Presser 80 foot —1— and feed portion 2 are formed with the usual aperture 4 having a width and length sufficiently adapted for permitting the access of needle 5 to the cloth disposed beneath presser foot —1—, relative 85 to the movements of feed portion 2 and cloth plate 3 of the machine. Post 6 is mounted on plate 3 and is surrounded by a coiled spring 7 which creates a pressure on plate 8 formed with arms 9 and 10 extending to opposite sides of presser-foot —1—, whereby to exert a yielding downward pressure thereon. Presser foot —1—, arms 9 and 10, and plate 8 are elevated in the well known manner by mechanism not herein 90 shown in detail. Furthermore, cloth plate 3 is shifted longitudinally and transversely by cam mechanism situated beneath the machine, whereby the cloth is moved relative to needle 5 for enabling the stitching by said 95 needle 5 of the respective sides of the button-hole. Presser foot —1— and feed portion 2 are shifted simultaneously with cloth plate 3 for the aforesaid purpose. Needle 5 in addition to the regular reciprocation, is 100 oscillated through an arc equal to the length of the stitch at one side of the button-hole, or the distance represented from point 11 to point 12 in Fig. 15.

The parts above referred to are well 110

known in the art and are mentioned merely for a better understanding of the attachment now to be described.

In Letters Patent granted to me May 7, 1912, No. 1,025,574, there is shown certain parts which are employed also here, namely filler block 13, depending plate or bracket 15, slotted for receiving retaining screws 16-16, whereby said bracket may be adjustably held to head 17. The lower end of bracket 15 has a horizontal portion 18 bent outwardly, and a horizontal portion 19 bent inwardly. Said horizontal portion 19 supports in a depending manner a journal bearing block 20, by means of screw 21. Block 20 is bifurcated, whereby to support there-between sleeve 22 holding adjustable guide 23 by means of set screw 24 and mounted upon rock shaft 25 having its outward end bent upwardly as at 26 adapted to be engaged by a retractile spring 27 whose remote end is in engagement with rod 28 supported by its bearing in post 29 extending laterally from the side of the machine. The end of rod 28 is screw threaded for the corresponding mounting of caps or lock nuts 30-30, so that rod 28 may be moved longitudinally to adjust the tension of spring 25. Sleeve 22 is held to rock shaft 25 by set screw 31. The lower end of guide 23 is disposed adjacent needle 5, and is provided with a feeding aperture 33 through which is delivered a stay cord 34 from cord tension device 35, not disclosed in the former application.

In order to provide means, whereby guide 23 will register with opening 4 of presser-foot —1— and of feed portion 2, at the completion of a button-hole in the cloth, when presser-foot —1— is in its rearmost position, there is mounted on rock shaft 25, between sleeve 22 and the portion adjacent the upward bend, namely 26, a novel sleeve 36 holding a rod 37 by set screw 38. The outer end of rod 37 is connected by a wire 32 or other suitable means to post 39a of belt shifter 39 at the rear of the machine, so that the movement of belt shifter 39 will be transmitted through said rod or wire 32, rod 37 and sleeve 36, to rock shaft 25 and its connected parts sufficiently to cause the lower end of guide 23 to move rearwardly whereby to register with aperture 4 of presser-foot —1—, and thereby permit the elevation of presser foot —1— to move the cloth underneath to the location of the next button-hole.

In the button-hole sewing machine of the foregoing type, the needle 5 remains stationary with reference to the movement, longitudinal and transverse of the button-hole, so that it is necessary only to move guide 23 with reference to needle 5 to permit stay cord 34 to be delivered in advance of needle 5, throughout the button-hole. To

effect this purpose, there is provided further novel means for rocking shaft 25. Said means comprises a standard 40 secured to cloth plate 3 of the machine and having its upper end recessed at 41 for the reception of stop lever 42 pivoted at 43 to the outwardly extending portion 18 of bracket 15. To the forward portion of lever 42, in front of pivot 43, is laterally secured a guide flange 44 having a portion projecting laterally above its base to form a guide way for dog 45 provided with a corner recess 46 and a central recess 47 adapted to clear pivot 43. Dog 45 is constrained from leaving the upper surface of lever 42 in a lateral manner by plate 48 secured at one end to bracket 50 mounted on lever 42. The free end of plate 48 is supported by laminated spring 49 secured also at one end to stud 50. Dog 45 is connected to belt shifter 39 by an arm 51 having an adjustable joint at 52, whereby the movement of belt shifter 39 actuates or longitudinally reciprocates dog 45.

Located underneath lever 42 is a certain novel longitudinally adjustable bar 53 secured to lever 42 by set screws 54-54 and having one side projecting a short distance outward from the corresponding side of lever 42.

The operation of the device is as follows: The cloth is disposed beneath presser foot —1— at the proper place for the location of a button-hole therein, whereupon the operator lowers the presser-foot and throws on the power, whereby belt shipper 39 is moved forwardly to ship the belt from idle pulley 56 to power pulley 57. This movement of the belt shipper 39 is sufficient to cause dog 45, connected thereto by rod 51, to abut against the upper portion 26 of lever 25, whereby to rock said lever and its connected parts including guide 23, so that said guide 23 is moved to the rear of needle 5 or to the position indicated in Fig. 1 in advance of the relative direction of travel of needle 5 along the first side of the button-hole. The parts maintain this relative position while the cloth is moving forwardly throughout the first side of the button-hole, as seen more particularly in Fig. 15. At the completion of the aforesaid side, cloth plate 3 and the correlated parts are shifted transversely, whereby needle 5 assumes a position above the opposite side of the button-hole. The transverse movement of cloth plate 3, causes a simultaneous movement of standard 40, which correspondingly moves lever 42 and its immediate parts upon pivot 43. To the rear end of said lever 42, there is attached a coiled spring 60 tending to normally draw the rear end of lever 42 inward, when standard 40 moves forward, as shown in dotted lines in Fig. 3. The opposite end of spring 60 is

secured to any suitable part of the machine as to the forked end 62 of arm 63. The aforesaid movement of lever 42 causes recess 46 of dog 45 to register with portion 26 of rock shaft 25, whereby said arm is rocked or journaled to permit guide 23 to assume a position in front of needle 5. The function of longitudinally adjustable bar 53, at this instance is employed to permit lever 42 to move to the position shown in dotted lines in Fig. 3, immediately the respective sides of recess 41 of standard 40 reach the forward end as at 65 of the projecting portion of longitudinally adjustable bar 53 and before presser plate —1— and connected parts are shifted completely transversely of the button-hole for causing the needle 5 to assume a position above the opposite side of the button-hole, so that 20 guide 23 will be out of the way of needle 5, when barring the button-hole, as at 66. In this last mentioned position, the upper portion 26 of rock shaft 25 lies in recess 46 of dog 45.

25 The employment of longitudinally adjustable bar 53 will be found particularly useful in view of the fact that guide 23 would not otherwise move ahead until the presser-plate —1— and connected parts had 30 shifted completely transversely of the button-hole for causing the needle 5 to assume a position above the opposite side of the said button-hole, as in the patent herein above referred to.

35 In Figs. 5, 6, 7, and 8, there is shown a modification of the means for causing guide 23 to move in a manner to precede needle 5, when stitching the sides of the button-hole. The modification embodies an arm 70 pivotally secured to the bifurcated portion of bearing 71, which is fulcrumed upon bracket 72 secured to the head of the machine, whereby there is formed a universal joint. To the lower end of arm 70 there is detachably secured a lug 73 holding an adjustable guide 74 by means of set screw 75. Guide 74 has the same function as guide 23 of the former construction. A bracket 76 is secured to the head of the machine and pivotally supports at 77 a lever 78, whose outer end is connected by wire 79 or other means to post 39^a of belt shipper 39 of the machine. Lever 78 is provided with a curved recess 80, whereby the edge of said recess will engage with arm 70 and, at the proper interval, force same outwardly and rearwardly. The mechanism for causing arm 70 to assume the position shown in dotted lines in Fig. 5, embodies a lever 81 having notches 82 and 45 83 and a tapering end portion 84. Lever 81 is pivotally connected to bell crank lever 85 fulcrumed at 86 to the upper portion 87 of bracket 88, having a lower portion 89, provided with slot 90, whereby said bracket 50 88 may be held in an adjustable manner by

set screws 91—91. The portion 89 of the bracket 88 is secured to the base plate of the sewing machine, whereby the bracket 88 is held stationary, and independent of the movement of the presser plate 3. The end 70 92 of bell crank lever 85 is pivotally secured to link 93, pivotally mounted to the upper surface of post 94 by screw 95. Post 94 is mounted upon cloth plate 3, whereby its movements will be imparted to post 94 and its connected parts including lever 81. Lever 81 is held normally in the position shown in full lines in Fig. 7 by a spring 96 connecting end 97 of lever 81 and set screw 98 mounted to bell crank lever 85, and by adjustable member 99 mounted upon bell crank lever 85 by set screw 98, and having a reduced end 100 adapted to abut against a corresponding recess 101 formed in lever 81. In this position the free end of lever 81 will lie adjacent the inner surface of arm 70, held normally in toward the head by coil spring 102, connecting arm 70 and any suitable portion of the head as screw 103 supporting bracket 76. Arm 70 is moved to 80 the position shown in full lines in Fig. 5 by the edge of lever 78, which is journaled upon its pivot 77 to the position shown in full lines in Fig. 7 by wire 79 connecting the outer end of lever 78 with belt shipper 39, as said shipper moves rearwardly to throw the belt from power pulley 57 to idler 56. Guide 74 remains in this last named position, or in the rear or relative advance of 85 needle 5, while same is stitching the first side of the button-hole. At the conclusion of stitching of the button-hole, the automatic transverse shifting of cloth plate 3, presser-foot —1— and feed 2 causes a simultaneous movement of post 94, and its connected parts, namely link 93, bell crank lever 85, and lever 81 to the position indicated in dotted lines in Fig. 7, so that lever 81 is drawn rearwardly a sufficient distance to permit notch 83 thereof to engage the 90 edge of arm 70. The subsequent automatic transverse movement of plate 3, at the completion of the first side of the button-hole, whereby the cloth is shifted transversely to permit needle 5 to be disposed over the opposite side of the button-hole, causes a forward movement of lever 81, which being in engagement at notch 82 with arm 70, will 95 actuate said arm 70 forwardly to the position shown in dotted lines in Fig. 5. In this last mentioned position of arm 70, guide 74 will be moved to the front of needle 5. Obviously, lever 78 will be in the position indicated by dotted lines in Fig. 7, when this last named forward movement of arm 70 occurs, for when belt shipper 39 moves forwardly to throw the belt from idle pulley 56 to power pulley 57, the same will cause wire 79 to move lever 78 to the dotted line 100 position indicated in Fig. 7. Arm 70 will 105 110 115 120 125 130

remain in this second position, while needle 5 is stitching the second side of the button-hole. At the conclusion of the second side of the button-hole, shipper 39 will automatically move rearwardly, and by means of wire 79, draw lever 78 again to the position indicated by full lines in Fig. 7, whereby guide 74 will be positioned for the next button-hole to be formed. The automatic transverse shifting of the cloth plate 3 and correlated parts at the conclusion of the formation of a button-hole, as stated, will move lever 81 to the position indicated in dotted lines in Fig. 7, whereby said lever 81 will be drawn rearwardly sufficiently to permit notch 83 thereof to engage the edge of arm 70, so as to be ready to push arm 70 forward or into the dotted line position indicated in Fig. 5, at the conclusion of forming the first side of the button-hole.

In the modified form just above described, guide 74 does not move under needle 5 in its passage from one side to the other of said needle, but oscillates around needle 5. The mechanism provided to effect this oscillatory movement, contemplates a roller 105, loosely mounted to a pivot 106, secured to bracket 76, against which abuts the end of a screw 107, threaded to arm 70, so as to regulate the degree of arc described by the end of guide 74 about needle 5. A depending member 108 is secured to one end of lever 78, whereby to provide a stop for lever 81, so that said lever will just clear arm 70, when said lever is in the full line position indicated in Fig. 7.

A still further modification of the corded attachment is shown in Figs. 11 and 12, in which construction, arm 70 is moved rearwardly and forwardly to either side of needle 5 by link 110 pivotally connected at 111 to bell crank lever 112, fulcrumed at 113 to bracket 114, secured to the head of the machine. End 115 of lever 112 is pivotally connected to link 116 fulcrumed at 117 to post 118, mounted upon cloth plate 3 of the machine. The movement of cloth-plate 3 will cause a corresponding movement of post 118, link 116, bell crank lever 112, and link 110, whereby the movements of cloth-plate 3 will be communicated to arm 70 to cause same to move guide 74 holding the cord relative to needle 5. Arm 70, as in the former modified construction, is oscillated about needle 5. To effect which movement, a roller 105 is employed and adapted to ride over a curved shaped projection 120 mounted in alinement therewith on arm 70. Projection 120 of arm 70 is aided in passing roller 105 mounted to bracket 76 by the cam portion 121 of sliding member 122, provided with elongated slot 123 adapted for the passage of headed bolt 124, secured to bracket 125, mounted upon the head of the machine. Member 122 is connected by rod

or arm 126, as shown at 51 in Fig. 1, to belt shipper 39, whereby cam portion 121 will be moved in unison with shipper 39, to force arm 70 outwardly against the tension of spring 130, at the time arm 70 is moved to the position shown in full lines in Fig. 5.

The modification illustrated in Figs. 5, 6 and 11 is particularly desirable in view of the fact that guide 74 being shifted from one side of needle 5 to the other, by the action of cloth plate 3, permits the movements of guide 74 to be gradual, whereby the cord 34 is completely covered by the needle stitches in the fabric about the button-hole. Particularly is this so with reference to the ends of the button-hole, where the transfer of guide 74 takes place, from one side of needle 5 to the other.

Having thus described my invention, what I claim as new and desire to secure by Letters Patent is:

1. In a buttonhole sewing machine, the combination of a needle, means for controlling the actuation of said needle, an adjustable guide, a head, a bracket secured to said head, a bearing pivotally connected to said bracket, an arm pivotally connected to said bearing and supporting said adjustable guide, a lever for moving said arm to one side of said needle, and a lever actuated by the means that controls the actuation of said needle, whereby to move said arm to the opposite side of said needle.

2. In a buttonhole sewing machine, the combination of a needle, means for controlling the actuation of said needle, a head, a guide, means for moving said guide from one side to the other of said needle, said means comprising an arm pivotally secured to said head, a cloth plate, a lever actuated by the movement of said cloth plate, whereby to move said arm into one position, and a lever actuated by the means that controls the actuation of said needle, whereby to move said arm to the reverse position.

3. In a buttonhole sewing machine, the combination of a needle, means for controlling the actuation of said needle, a guide, an arm pivotally mounted to said machine for supporting said guide, a cloth plate, a lever actuated by the movements of said cloth plate for moving said arm in one direction, whereby said guide will be disposed on one side of said needle, and a lever actuated by the means that controls the operation of the needle, whereby to move said arm in the reverse direction, so that said guide will be disposed on the opposite side of said needle.

4. In a buttonhole sewing machine, the combination of a needle, means for controlling the actuation of said needle, an adjustable guide, an arm for supporting said guide, a lever for moving said arm in one direction, whereby said guide will be dis-

- posed on one side of said needle, a cloth plate, means connected with said cloth plate for actuating said lever, a second lever for moving said arm in the reverse direction, 5 whereby said guide will be disposed on the opposite side of said needle, and means connected with the means that controls the operation of the needle, whereby to actuate said second named lever.
- 10 5. In a buttonhole sewing machine, the combination of a needle, means for controlling the actuation of said needle, an adjustable guide, a cloth plate, means actuated by the movement of the cloth-plate, for moving 15 said guide to one side of said needle, and a lever actuated by the means that controls the operation of said needle, whereby to move said guide to the opposite side of said needle.
- 20 6. In a buttonhole sewing machine, the combination of a needle, means for controlling the actuation of said needle, a guide, a cloth-plate, means actuated by the movement of the cloth-plate, whereby to actuate said 25 guide to one side of said needle, a lever actuated by the means that controls the reciprocation of said needle, whereby to move said guide to the opposite side of said needle, and means for causing said guide to oscillate 30 about said needle.
7. In a buttonhole sewing machine, the combination of a needle, means for controlling the actuation of said needle, a guide, an arm, means connecting said guide with 35 said arm, a lever for moving said arm in one direction, a cloth plate, means connecting said lever with said cloth-plate, whereby the movement of said cloth-plate will be communicated to said lever, a lever having 40 a notch for moving said arm in the reverse direction, means connecting said last named lever with the means that controls the operation of said needle, whereby said needle controlling means may control said last named 45 lever.
8. In a buttonhole sewing machine, the combination of a needle, means for controlling the actuation of said needle, a guide, an arm supporting the guide, a head, means 50 for connecting said arm with said head, a cloth-plate, a lever actuated by the movement of said cloth-plate, whereby to move said arm and guide to one side of said needle, said lever adapted to be withdrawn from 55 contact with said arm, a second lever, a bracket upon which said second lever is fulcrumed, whereby to contact with said arm to move same to the opposite side of said needle, means for actuating said second lever, and means for causing said guide to 60 oscillate about said needle.
9. In a buttonhole sewing machine, the combination of a needle, means for controlling the actuation of said needle, a guide, adapted to be moved from side to side of 65
- said needle, a lever, a wire connected to said lever and to the means that controls the actuation of said needle, whereby said lever may move said guide to one side of said needle, a second lever having a notch, whereby to move said guide to the opposite side of said needle, and means for actuating said second named lever. 70
10. In a button-hole sewing machine, the combination of a needle, means for controlling the actuation of said needle, a guide, an arm pivotally supported by said machine whereby to mount said guide, a lever for moving said guide to one side of said needle, a bell crank lever pivotally connected with 75 said lever, a cloth-plate, a post secured to said cloth-plate, whereby to actuate said bell crank lever, a third lever connected with the means for controlling the actuation of said needle, whereby to move said guide to the 80 opposite side of said needle.
11. In a buttonhole sewing machine, the combination of a needle, a guide, a lever, for moving said guide to one side of said needle, a second lever for moving said guide 85 to the opposite side of said needle, means for actuating said levers, and a roller for causing said guide to oscillate about said needle. 90
12. In a button-hole sewing machine, the combination of a needle, a guide adapted to be moved from one side to the other of said needle, a lever for moving said guide to one side of said needle, a second lever for moving said guide to the opposite side of said 95 lever, means for actuating said levers, and means for causing said guide to oscillate about said needle, said last named means comprising a roller and an adjustable set screw. 100
13. In a buttonhole sewing machine, the combination of a needle, a guide, an arm pivotally mounted to the machine, a lever for moving said arm and guide to one side of said needle, a second lever for moving 105 said arm and guide to the opposite side of said needle, a set screw mounted on said arm, a roller, a bracket, said roller connected to said bracket, secured to the machine, and means causing said set screw to move over 110 the surface of said roller, whereby said guide will oscillate about said needle. 115
14. In a buttonhole sewing machine, the combination with a needle, of an adjustable guide, an arm pivotally mounted to the machine for holding said guide, a lever for causing said guide to move to one side of said needle, a second lever for causing said guide to move to the opposite side of said needle, a roller, a bracket upon which said 120 roller is pivotally secured, and an adjustable screw adapted to contact with said roller during the passage of said guide from one side of said needle to the other, whereby said guide will oscillate about said needle. 125
- 65 9. In a buttonhole sewing machine, the combination of a needle, means for controlling the actuation of said needle, a guide, adapted to be moved from side to side of 130

15. In a buttonhole sewing machine, the combination of a needle, means for controlling the actuation of said needle, a head, an arm fulcrumed to said head, a guide supported by said arm, means for adjusting in a vertical manner said guide, a lever having a notch, whereby to move said arm to one side of said needle, a lever actuated by the means that controls the actuation of said 10 needle, whereby to move said arm to the opposite side of said needle.

16. In a buttonhole sewing machine, the combination of a needle, a head, an arm pivotally mounted to said head, said arm supporting a guide, means for moving said arm to one side and then the other of said needle, and a roller and set screw for causing said 15 guide to oscillate about said needle.

17. In a buttonhole sewing machine, the combination of a needle, an arm holding an adjustable guide, a lever, a bracket which pivotally supports said lever, said bracket being secured to the machine, a belt shifter connected with said lever, whereby to move 20 said arm to one side of said needle, and a lever having a notch, whereby to move said arm to the opposite side of said needle.

18. In a buttonhole sewing machine, the combination of a needle, an arm holding a 25 guide, a cloth-plate, a bracket secured to said machine, a lever fulcrumed upon said bracket, a wire, a belt shifter, said wire connecting the free end of said lever with said belt shifter of the machine, whereby the 30 movement of said belt shifter will control said lever to move said arm to one side of

said needle, and a lever having a notch, a bell crank lever pivotally supporting said lever with a notch and actuated by the movement of said cloth-plate, whereby said arm 40 will be moved to the opposite side of said needle.

19. In a buttonhole sewing machine, the combination of a needle, a guide, a head, an arm, a bearing pivotally supported on said 45 head and supporting said arm, said arm adapted to hold said guide, automatic means for moving said guide to one side of said needle, a lever, a wire, and a belt shifter, said wire connecting said lever with said belt 50 shifter, whereby to move said guide to the opposite side of said needle.

20. In a buttonhole sewing machine, the combination of a needle, a head, an arm fulcrumed upon said head, a guide held by 55 said arm, automatic means for moving said arm and guide to one side of said needle, a lever having a notch for engaging said arm, whereby to move said arm to the opposite side of said needle, a bell crank lever adapted to pivotally support said lever having a 60 notch, a spring and an adjustable member for holding said lever having a notch in normal position, whereby said lever will engage said arm.

In testimony whereof I have affixed my signature in the presence of two witnesses.

FRANK M. KENNEDY.
